(57) **CLAIM**

The ornamental design for a cooktop or portion thereof, as shown and described.

DESCRIPTION

FIG. 1 is a top perspective view of a first embodiment of a cooktop or portion thereof showing the new design.

FIG. 2 is a top view of the embodiment of FIG. 1.

FIG. 3 is a front view of the embodiment of FIG. 1.

FIG. 4 is a side view of the embodiment of FIG. 1.

FIG. 5 is another side of the embodiment of FIG. 1.

FIG. 6 is a bottom view of the embodiment of FIG. 1.

FIG. 7 is a rear view of the embodiment of FIG. 1.

FIG. 8 is a top perspective view of a second embodiment of a cooktop or portion thereof showing the new design.

FIG. 9 is a top view of the embodiment of FIG. 8.

FIG. 10 is a front view of the embodiment of FIG. 8.

FIG. 11 is a side view of the embodiment of FIG. 8.

FIG. 12 is another side view of the embodiment of FIG. 8.

FIG. 13 is a bottom view of the embodiment of FIG. 8; and, FIG. 14 is a rear view of the embodiment of FIG. 8.

The broken lines shown in the figures are for the purpose of illustrating portions of a cooktop and form no part of the claimed design.
